UNITED STATES PATENT OFFICE

HERMANN STROTHOFF, OF DUISBERG, GERMANY, ASSIGNOR TO THE BABCOCK & WILCOX COMPANY, OF NEW YORK, N. Y.

STEAM GENERATOR

Application filed February 26, 1925, Serial No. 11,881, and in Germany February 26, 1924. Renewed September 8, 1932.

This invention relates to a water tube boiler having sectional headers of sinuous formation connected by staggered rows of inclined tubes.

According to the invention the header sections at one end of the stack of tubes are laterally offset or displaced relatively to the header sections at the other end, so that adjoining header sections are interconnected

by way of the water-tubes, whereby, say in the adaptation of the invention to a unit comprising two steam and water drums extending side by side, at least one vertical staggered row comprises tubes alternate ones

of which are connected to header sections coupled to one drum, while the other tubes of that row are connected to header sections coupled to the other drum, so that, with the drums communicating with one another in this way, balancing of the condition of the water contents of the two drums is assured as to concentration of solids and water level.

The invention is of particular importance in connection with boilers for high pressures and small water contents (pressures up to 40 to 100 atmospheres).

More especially in the adaptation of the invention to a high pressure boiler there may be substituted for the usual upper steam and water drum an upper tubular system comprising header sections connected by preferably slightly inclined tubes and arranged as above described, these header sections being connected with the associated header sections of the generating system.

Preferably the tubes of the bottom horizontal row of the upper system are uniform in diameter—the same as the tubes of the generating system—and adapted to hold cover plates which cut the upper system out of the path of the gases, while the remaining tubes of the upper system are of relatively large diameter but bottle-necked or contracted at the ends where they are expanded into the header sections.

The invention is illustrated in the accompanying drawings, in which Fig. 1 is an elevation of part of a water tube boiler; Fig. 2 is a section on the line 2—2 of Fig. 1; Fig. 3 is a section on the line 3—3 of Fig. 2; Fig.

4 is a fragmentary view, drawn to a larger scale, looking in the direction of the arrow E in Fig. 1; Fig. 5 is a longitudinal section of a modified construction of water tube boiler; Fig. 6 is a part rear elevation part section on the line 6—6 of Fig. 5, and Fig. 7 is a view generally similar to Fig. 3 illustrating the offset relation of the headers of the upper tubular system of Figs. 5 and 6.

The boiler shown in Figs. 1—4 comprises a pair of upper steam and water drums 3, 4, coupled at the ends to sinuous headers connected by inclined tubes.

As will be seen from the figures, the water tubes 1 from the header section 5 lead at 1a into the opposite header section 6, which again communicates by way of the tubes 2a, 2, with the header section 7. The remaining header sections 7—12 are similarly interconnected. Successive tubes connected to a given header, therefore, are connected alternately to two adjacent headers at the opposite end of the boiler, so that there are tubes connected to a header in one unit which communicate with adjacent drums of two units through the adjacent headers at the opposite end of the boiler to which the said successive tubes are connected. The tubes connected to a given header at one end of the drum, therefore, are divided into two groups connected respectively to adjacent headers at the opposite end of the boiler.

In the modified construction shown in Figs. 5 and 6 there is substituted for the upper longitudinal drums an upper tubular system comprising sectional headers 13, 14, interconnected by slightly inclined tubes 15 in the manner described in connection with Figs. 1—4.

As will be observed, the tubes 16 of the bottom horizontal row of the upper system are of the same diameter as the generating tubes 17 and serve to hold cover plates 18 which cut the tubes 15 out of the path of the gases. With the tubes 15 thus cut out of the path of the gases the deposit of large quantities of boiler scale in these tubes is not to be feared. It is thus practicable to employ larger tubes, bottle-necked at the ends, whereby the water and steam space is in-

creased—the contraction of the tube diameters at the expanding points rendering the latter better able to withstand high pressures. There are thus, in the arrangement 5 illustrated in Figs. 5 and 6, two upper steam and water separating sections. The arrangement here illustrated is particularly applicable to high-pressure boilers and where the drums would necessarily be of abnormal 10 thickness. One of the advantages of such an arrangement is that in case of damage due, for example, to corrosion, the damaged tubes may be replaced without disturbing other tubes of the boiler, whereas with a 15 drum, in case of such damage, the entire drum must be replaced.

I claim:—

1. A water tube boiler comprising a generating system and a steam and water separating system located above said generating system, each system including sectional headers, the headers of the generating system at each end of the tubes communicating with the associated headers of the separating system, tubes connecting said headers, tubes of the upper system having a larger diameter throughout the major portion of their length than the tubes of the generating system, tubes of the upper section being contracted at their ends where they enter the headers whereby they may be more closely spaced than would otherwise be possible, and a baffle disposed above said generating system for cutting the major portion of said steam and water separating system out of the path of the hot gases.

2. A water tube boiler comprising a generating system including spaced water chambers connected by inclined tubes over which the gases flow and a steam and water separating system located above said generating system, said separating system comprising fluid chambers and tubes connecting said fluid chambers, said generating system 40 communicating with said separating system and forming a circulation therewith, and means for cutting the major portion of said separating system out of the path of the hot 45 gases, the tubes of said separating system having diameters greater throughout the major portion of their length than those of the generating system.

3. A water tube boiler comprising a generating system including spaced water chambers connected by inclined tubes over which the gases flow and a steam and water separating system located above said generating system, said separating system comprising fluid chambers and tubes connecting said fluid chambers, said generating system 55 communicating with said separating system and forming a circulation therewith, and means for cutting the major portion of said separating system out of the path of the hot 60 gases, the tubes of said separating system having diameters greater throughout the major portion of their length than those of the generating system.

gases, the tubes of the upper section being contracted where they enter said fluid chambers.

4. A water tube boiler comprising steam and water chambers located at the respective ends of the boiler, a steam generating system comprising inclined tubes located in the path of the furnace gases and communicating at their ends with the respective chambers, the gases flowing upwardly over said tubes of said generating system, a steam and water separating system comprising substantially horizontal tubes connected at their ends to said steam and water chambers and located above said generating system, the diameters of the tubes of said separating system being greater than those of the generating system and contracted at their ends where they enter said water chambers, and means for cutting the major portion of said separating system out of the path of the hot gases.

5. In a water tube boiler, a steam generating system comprising headers located at the respective ends of the boiler and connected by inclined tubes located in the path of the furnace gases, a steam and water separating system located above the steam generating system and comprising headers located at the respective ends of the boiler and tubes connecting said headers, the diameters of which are greater throughout the major portion of their length than those of the generating system, nipples connecting the headers for the generating system to those of the separating system, and means for cutting the major portion of said separating system out of the path of the hot gases.

6. A water tube boiler comprising a generating system including spaced water chambers connected by inclined tubes over which heating gases flow, a steam and water separating system located above said generating system, said separating system comprising steam and water chambers and tubes connecting said water chambers, said generating system communicating with said separating system and forming a circulation therewith, the water chambers at one end of said separating system being inter-connected, and means for cutting the major portion of said separating system out of the path of the hot gases, tubes of said separating system having diameters greater throughout the major portion of their length than those of the generating system.

7. A water tube boiler comprising a generating system including spaced water chambers connected by inclined tubes over which heating gases flow, and a steam and water separating system located above said generating system, said separating system comprising fluid chambers and tubes connecting said fluid chambers, said generating system communicating with said separating system and forming a circulation therewith, the tubes of

the separating system being contracted where they enter said fluid chambers.

8. A water tube boiler comprising a generating system including water chambers connected by inclined tubes over which heating gases flow, and a steam and water separating system located above said generating system, said separating system comprising fluid chambers and tubes connecting said fluid chambers, said generating system communicating with said separating system and forming a circulation therewith, the tubes of the separating system being inclined oppositely to the inclination of the tubes of the generating system, the tubes of the separating system having diameters greater throughout the major portion of their length than those of the generating system.

In testimony whereof I have signed my name to this specification.

HERMANN STROTHOFF.
